(57) **CLAIM**

The ornamental design for a package and packaging sheet for foodstuff, as shown and described.

DESCRIPTION

FIG. 1 is a front perspective view of a package and packaging sheet for foodstuff according to a first embodiment of our new design;

FIG. 2 is a front elevation view thereof;

FIG. 3 is a rear elevation view thereof;

FIG. 4 is a first side view thereof;

FIG. 5 is a second side view thereof;

FIG. 6 is a top plan view thereof;

FIG. 7 is a bottom plan view thereof;

FIG. 8 is a front perspective view of a package and packaging sheet for foodstuff according to a second embodiment of our new design;

FIG. 9 is a front elevation view thereof;

FIG. 10 is a rear elevation view thereof;

FIG. 11 is a first side view thereof;

FIG. 12 is a second side view thereof;

FIG. 13 is a top plan view thereof; and,

FIG. 14 is a bottom plan view thereof.

The broken lines in the drawings illustrate portions of the package and packaging sheet for foodstuff that form no part of the claimed design.

The packaging sheet for foodstuff illustrated in each of FIGS. 8-14 corresponds directly to the package for foodstuff illustrated in FIGS. 1-7, respectively. Each packaging sheet for foodstuff illustrates the corresponding package for foodstuff in collapsed form.
